J. B. FRANCISCO,
AUTOMOBILE HEATER.
APPLICATION FILED MAR. 10, 1920.

1,429,332.

Patented Sept. 19, 1922.

UNITED STATES PATENT OFFICE.

JOSEPH B. FRANCISCO, OF COLUMBUS, OHIO.

AUTOMOBILE HEATER.

Application filed March 10, 1920. Serial No. 364,723.

To all whom it may concern:

Be it known that JOSEPH B. FRANCISCO, a citizen of the United States, residing at Columbus, in the county of Franklin and 5 State of Ohio, has invented certain new and useful Improvements in Automobile Heaters, of which the following is a specification.

This invention relates to improvements in automobile heaters, and has for its object 10 to provide simple, yet efficient means capable of operating in connection with the exhaust manifold of an internal combustion engine for the purpose of leading or introducing heat radiated from said manifold into the 15 interior of the vehicle body.

The invention consists essentially in the provision of a sheet metal tube wherein is provided a plurality of laterally disposed manifold receiving openings in which the 20 branch conduits of the exhaust manifold are positioned, said tube being split longitudinally in order that the longitudinal edges thereof may be positioned in overlapped relation, and clamping means are 25 associated with the tube so as to circumferentially contract the latter and to thereby effect a firm and positive securing of the tube in clamped relationship with the exhaust manifold, the construction being such 30 as to permit this end to be accomplished with ease and facility.

Other objects will be in part obvious and in part pointed out hereinafter.

The invention accordingly consists in the 35 novel features of construction, combinations of elements and arrangements of parts, hereinafter to be fully described and to have the scope thereof pointed out in the appended claim.

40 In the accompanying drawings, forming a part of this specification, and in which similar characters of reference denote like and corresponding parts:

Figure 1 is a side elevation disclosing the 45 improved heater comprising the present invention as applied to the exhaust manifold of an internal combustion engine.

Figure 2 is a similar view looking toward the inner face of the heater.

50 Figure 3 is an enlarged transverse sectional view disclosing more particularly the clamping means.

Figure 4 is a detail longitudinal sectional view taken through the rear or discharge end of the heater.

Figure 5 is a detail transverse sectional view disclosing the fan draft adjusting mechanism, and,

Figure 6 is a rear elevation disclosing the discharge door of the heater.

In its preferred embodiment, the present invention consists of a vehicle heater 1 which is adapted to be employed in conjunction with the exhaust manifold 2 of an internal combustion engine 3. Through the provision of the heater 1, the radiated heat of the manifold 2 is confined and collected and delivered to the body of the vehicle with which the engine 3 is employed, for the purpose of heating the interior thereof. To accomplish this office, the heater consists of an elongated metal tube 4, which is split longitudinally as is indicated by the numeral 5 whereby the tube may be rigidly fastened in connection with the manifold. As shown in Figure 2, the inner portion of the tube is formed with suitable openings 6 which are arranged in such manner as to be capable of receiving the cylinder branches of the manifold 2 and these openings are of such proportion that the main body of the manifold will be concentrically located within the interior of the tube and substantially spaced from the inner walls of the latter, thus allowing for a circulation of air around the manifold and within the heater. The front end of the tube 4 is open and is so positioned as to lie immediately to the rear of the automobile radiator 7. The position of this forward portion of the tube is of prime importance, inasmuch as it insures the delivery of fresh air only to the interior of the tube and precludes obnoxious motor odors or gases.

The rear end of the heater is provided 95 with a removable section 8, the latter is of tubular form and is arranged to be longitudinally telescoped into connection with the rear end of the tube 4. The section 8 and the tube 4 are provided with cooperating 100 recesses 9 which are so disposed relatively that the downwardly bent end of the manifold 2 may project through such recesses and out of the heater. Manifestly, by the pro-

vision of the section 8 the heater is readily adapted to the structural formation of the manifold 2 without permitting of the undue escape of heated air from the confines of 5 said heater. The rear end of the section 8 may be terminated within the cowl construction 10 of the vehicle with which the heater is employed. Thus, through the provision of the construction described, when the vehicle 10 is in motion air will be forced through the tube 4 and brought into intimate contact with heat radiated from the manifold 2. This heated draft of air is then conducted rearwardly and discharged into the interior 15 of the vehicle body. It will be observed that the present invention does not let the exhaust gases of the engine into the vehicle body and hence may be safely operated. The discharge end of the section 8 is provided 20 with a transversely disposed guide plate 11 which is situated just within the cowl construction 10 of the vehicle. This plate carries a sliding valve plate 12 by means of which the extent of opening of the discharge 25 end of the heater may be manually regulated, the position of the plate 12 being such that its manipulation may be effected in a convenient manner from the vehicle operator's normal position.

30 An essential feature of the present invention resides in constructing the heater 1 so that the same may be quickly secured in operative relationship in connection with the manifold 2. This is mainly accomplished by splitting the tube longitudinally as at 5, and then providing the tube with a plurality of circumferential straps 13. These straps are provided with spaced ears 14 through which clamping bolts 15 are disposed to extend, nuts 16 being provided upon the threaded ends of said bolts and adapted to be turned to contract the tube 4 circumferentially. Therefore, by tightening the nuts 16, it will be manifest that the longitudinal edges of the tube 4 may be drawn relatively so that said tube may be quickly and positively clamped in its applied and operative position, without the necessity of removing engine parts to effect this object.

45 As shown in Figure 5, the forward end of the tube 4 is provided with an elongated slot 17 whose effective width may be regulated by the provision of a rotatable sleeve 18, the latter being carried as shown, by the outer 50 end of said tube. This sleeve is provided with a slot 19 which is capable of being brought into or out of registration with the slot 17 so that the extent of opening of the latter may be regulated. When the vehicle 55 is moving the sleeve 18 may be so rotated as to cover the slot 17, thus permitting of an unhindered flow of air into the forward end of the tube. Therefore, in the event that the vehicle is standing still and

the motor is in motion, the sleeve 18 may be rotated so that the slot 17 will be fully or partially uncovered. When this is accomplished, the heater is susceptible to the draft influences created by the motor fan 20, which latter acts to provide an induced 70 draft through the heater and therefore serves to insure a delivery of heated air into the body of the vehicle even when the latter is stationary.

75 Preferably, the rear end of the tube 4 is provided with a slot 21, which is capable of being covered by means of a sliding door 22. This construction is such that by opening the slot 21 through the medium of the door 22, the heat contained within the tube 80 may be freely discharged from the heater and will not circulate rearwardly into the body of the vehicle. The door 22 is of considerable use when high temperatures are prevalent, inasmuch as it eliminates the necessity of removing the tube 4 from its applied position upon an engine and in winter 85 said door enables the temperature of the interior of the vehicle to be readily regulated.

90 From the foregoing description, taken in conjunction with the accompanying drawing, it will be apparent that the present invention provides a heater of simple yet efficient construction, and one fully capable of 95 carrying out its various ends. The construction of the heater is such that the same may be readily and easily applied in a fixed manner to the manifold of an internal combustion engine, and eliminates the necessity of 100 removing engine parts to effect its application. The band construction 13 in combination with the longitudinal joint 5 provided in the heater enables the latter to be quickly and positively clamped around the 105 manifold and effectively serves to prevent the heater from losing its applied position around the manifold and also eliminates undue escape of the heated air passing through the tube. The various dampers associated 110 with the heater are so constructed and positioned as to control the flow of heat within the tube 4 in any desired manner and thus enables the heater to be comfortably adapted to the existing climatic conditions.

115 To hold the tube 4 in proper spaced relation with respect to the manifold 2, resilient bands 23 are provided, said bands being disposed transversely within the tube and have their ends fixed thereto, as shown 120 in Figure 5 of the drawing. When the tube is contracted through the medium of the straps 13, the bands 23 will yieldably engage the manifold 2 and firmly hold the tube in proper position thereon.

125 What is claimed is:

An automobile heater comprising a tube adapted to encircle the exhaust manifold of

an internal combustion engine, bowed resili-
ent bands disposed transversely in the tube
and having their ends fixed to the tube, said
bands being adapted to yieldably engage the
5 exhaust manifold, the ends of the tube being
open to permit passage of air therethrough,
said tube being split longitudinally and hav-

ing the edges overlapped, and means for
drawing said edges together whereby the
bands yieldably engage the manifold to 10
hold the same in clamped relation with said
manifold.

In testimony whereof I affix my signature.
JOSEPH B. FRANCISCO.
